Edwin P. Bent

ATTORNEY.

UNITED STATES PATENT OFFICE.

FREDERICK H. SCHWARTZ, OF COLUMBUS, OHIO.

DISAPPEARING-DOOR STRUCTURE.

Application filed September 7, 1923. Serial No. 661,516.

To all whom it may concern:

Be it known that I, FREDERICK H. SCHWARTZ, a citizen of the United States of America, residing at Columbus, in the 5 county of Franklin and State of Ohio, have invented certain new and useful Improvements in Disappearing-Door Structures, of which the following is a specification.

My invention relates to disappearing door 10 structure, for display cabinets, show cases and the like. It has to do with the provision of a novel and particularly simple means for guiding and supporting the weight of the sliding door structure.

15 In the past, various methods and means have been used for effecting the swinging of display cabinet doors from a closed position to an open disappearing position. Various types of display cabinets or cases 20 have been employed, which usually have the sides and back constructed of glass panels and the front closed by doors which move from closed position to an open position inside the case and parallel with the sides 25 thereof.

These sliding doors as commonly employed consist of two different but common designs. In one type, the doors are first 30 swung to extreme open position and then slid inside the case while in the other type the doors are swung laterally and inwardly with one continuous motion. In both of these types considerable difficulty has been experienced in the swinging of the doors due 35 to excessive friction and binding action as the door guides move in their respective tracks. Furthermore, in both types of doors the width of the display cabinet case is unnecessarily restricted by the relative 40 depth of such cabinets or cases for the reason that various means have been connected to the rear part of the door, both at the top and the bottom, for the purpose of guiding the door, preventing it from tilting and in 45 some cases forming a stile or separate pivoting means. These means have always been connected to the rear part of the door and have extended rearwardly for some distance, thus making it necessary to have the cabinet 50 of a materially greater depth than the width of one door.

55 My invention has to do primarily with the provision of means for supporting the weight of a sliding door with very little friction and for positively guiding the door so that it can be swung open or closed with

a free action and without binding. Furthermore, by my device the effective weight of a display cabinet door is counteracted by means which absorbs all such effective weight with comparatively little friction and such device is also effective to guide the door regardless of whether the door is moved straight out from the cabinet or in a curved path and in one continuous motion. 60

Furthermore, my invention is such that the depth of the cabinet need only be limited by the approximate width of the door itself.

More specifically, my invention comprises a guide and weight supporting means for a 70 sliding door structure, which door structure is preferably of the common type wherein the fulcrum of the door is placed off center in such a manner as to cause the rear portion of the door to be tilted upwardly. My guiding 75 and weight supporting means is preferably adapted to be attached to the rear upper corner of the door as a single compact unit which takes up very little space and which is easily applied or dismantled. The guiding means is so connected to the door as to bear a fixed relative position thereto while the door weight supporting means is preferably pivotally mounted on said guiding means and separated therefrom only by such 85 a distance as will give it a free turning movement.

The preferred embodiment of my invention is shown in the accompanying drawings wherein similar characters of reference 90 designate corresponding parts wherein:

Figure 1 is a fragmentary side elevation of a swinging or sliding door structure with my device applied thereto and showing the relative positioning of the guiding and supporting means.

Figure 2 is a plan view partially in section of the structure shown in Figure 1 and showing the manner of freely swinging the door relative to the guiding and supporting 100 means.

In the drawings the preferred embodiment of my invention is shown in combination with a display cabinet door which may be designated 1. This cabinet door 1 is 105 merely fragmentarily shown for the reason that my invention relates solely to the guiding and supporting of such door. It will be understood, however, that this door may form a part of a cabinet or case, the top 110 of which may be designated 2 and which is provided with suitable tracks both in the

top and bottom for the suitable guiding of the doors from a position parallel with the sides of the cabinet to a closed contacting position in the front of the cabinet and at 5 right angles to the sides of the cabinet. As far as the position of the novel device of my invention is concerned these doors may swing inwardly and laterally with one continuous motion in the well-known manner 10 or they may slide parallel with the sides of the cabinet and then swing to closed position about a pivot at the front corners of the cabinet.

As shown, the door is guided in its outward 15 and inward movement by means of a guide 3 which moves in a track 4 formed in the upper part of the cabinet and extending parallel with the sides thereof. In the drawings the side of the cabinet is diagrammatically shown and designated by the numeral 5, while the rear wall of the cabinet is diagrammatically shown as at 6.

The guide 3 preferably consists of a freely rotatable bearing or collar which slidably 25 fits within the track 4 and which is mounted upon a pin 7 carried by a suitable bracket 8. This bracket 8 preferably comprises two extensions 9 forming a bearing for the guide pin 7 and a rearwardly projecting arm 10 30 which is secured to the door by means of suitable screws or fastening means 11. The front part of the bracket 8 is also preferably secured to the door by means of a screw 12.

The door 1, the back part of which normally 35 tends to tilt towards the top of the cabinet, is supported by means of a roller bearing 13 which is freely movable within the track 4 and contacts with the top thereof. This roller bearing 13 is pivotally 40 mounted upon the guide pin 7 by means of a suitable yoke 14. As best shown in Figure 1, the yoke 14 and the bearing arms 9 of the bracket 8 are in alignment and are so aligned for the convenient reception of 45 the guide pin 7. This roller bearing 13 is of relatively large diameter so as to reduce all friction to a minimum and is only spaced apart from the guide 3 as will permit its free turning relative to such guide.

Referring especially to Figure 2 the door 1 and the arm 10 of the bracket 8 are shown in an angular position relative to the track 4 and the general line of movement of the guide 3 and its roller bearing 13. The 55 swinging of the door 1 may be independent of any movement of the guide 3 and the supporting bearing 13. It will thus be obvious that the guide bearing 3 and the supporting roller bearing 13 may be mounted 60 upon the door as a single unit which is of such form as will be easily attached to any door and which may be equally dismantled by simply removing the guide pin 7.

In operation, when it is desired to close 65 the door or doors, the same is moved from

the position shown in Figure 1 towards the front of the display cabinet. The guide bearing 3 which is preferably in alignment with a similar bearing in the base of the door, will move in the track 4 and thus 70 guide the door in its sliding movement. As the door is preferably supported by an off-center castor or other means, the rear of the door will be forced upwardly and this upward movement or weight of the door will 75 be counteracted and absorbed by the roller bearing 13. Regardless of whether the door 1 is pulled straight forward or is swung in a greater angle, as indicated in Figure 2, the roller bearing 13 will remain in alignment 80 with track 4 for the reason that it is pivotally mounted upon the bearing pin 7. Thus in any type of door the roller bearing 13 will support the weight of the door until it reaches the end of its outward stroke, at 85 which point the door will be in closed position parallel with the front of the cabinet and will be positively prevented from tilting in this closed position by the guide 3 which will contact with the sides of the straight track 4. The supporting and guiding of the door when moving from closed to open position will obviously be accomplished in the same manner as above described.

It will be seen I have provided a novel device for a disappearing door structure of such compact form that it may be applied to the doors as a single unit and which will at the same time take up such a small space in the rear of the door that the width of each door may be substantially equal to the depth of the cabinet. It will further be obvious that I have provided a means for positively guiding and positioning the door at all times and at the same time have provided means for effectively supporting the door whereby it can be operated freely without binding and with practically no friction.

From the illustrated embodiment of the invention herewith disclosed it will be obvious to all those familiar with the art that various shapes, sizes and combinations of guiding and supporting structure may be provided and it will also be clear that such combined guiding and supporting structure 110 may be mounted upon the door in different manners as may be desired.

Having thus described my invention, what I claim is:

1. Sliding door structure for display cabinets comprising a track, means for guiding the door by engaging said track and means pivoted to the shaft of said guiding means and bearing against the top of the cabinet for supporting the weight of the door, said supporting means being so positioned as to allow the rear of the door to slide approximately flush with the rear wall of the cabinet.

2. In combination with a sliding door

structure for display cabinets of a single unit mounted upon an upper corner of the door and comprising guiding and supporting means, the shaft of said guiding means

5 forming a pivoted connection between the supporting means and the door.

3. Sliding door structure comprising as a unit, a bracket, door guiding and support-

ing means, and a single pin forming a bearing for said guiding means and securing said 10 guiding and supporting means to said bracket.

In testimony whereof I have affixed my signature.

FREDERICK H. SCHWARTZ.
